UNITED STATES PATENT OFFICE.

HENRY C. FOLGER, OF WEST SOMERVILLE, MASSACHUSETTS, ASSIGNOR
TO AMERICAN COIL COMPANY, OF BOSTON, MASSACHUSETTS, A CO-
PARTNERSHIP.

IGNITION APPARATUS FOR GAS-ENGINES OR THE LIKE.

SPECIFICATION forming part of Letters Patent No. 768,793, dated August 30, 1904.

Application filed December 18, 1903. Serial No. 185,631. (No model.)

To all whom it may concern:

Be it known that I, HENRY C. FOLGER, a citizen of the United States, residing in West Somerville, in the county of Suffolk and State 5 of Massachusetts, have invented an Improvement in Ignition Apparatus for Gas-Engines or the Like, of which the following description, in connection with the accompanying drawings, is a specification, like letters on the 10 drawings representing like parts.

In certain classes of work, particularly in marine work, it has long been desired to employ the jump-spark form of apparatus in connection with gas-engines and the like; but the 15 tendency to short-circuit under such conditions has rendered this form of apparatus so unreliable as practically to exclude it from marine work, the secondary connections being liable to become short-circuited or have the 20 current dissipated unexpectedly by reason of the action of the salt water and dampness. It will be apparent that in marine work, as in no other class of work, it is vital that the 25 spark should be invariably certain—as, for instance, if on a lee-shore the sparking apparatus should break down the vessel is practically lost. If it were not for this unreliability, due to the short-circuiting of the secondary wire and connections, the jump-spark 30 form of apparatus would at once be used, as it is recognized to have more sparking efficiency and to be more economical in consumption of battery and wear and tear of parts.

Accordingly my invention has for its object 35 the provision of means for enabling this form of apparatus to be effectively adapted to the class of work above explained and also has for a further object the provision of means which will prevent the transmission of the current through the engine, thereby eliminating the serious objection heretofore existing in marine work of the liability of shock to the engineer.

My invention will be more fully understood 40 and more explicitly explained in the course of the following description, attention being di-

rected to the accompanying drawings, in which I have shown certain preferred embodiments of the invention, the latter being further defined in the appended claims.

50

In the drawings, Figure 1 is a bottom plan view of one form of the apparatus. Fig. 2 shows the same in side elevation, parts being broken away. Figs. 3 and 4 are sectional details on the lines 3 3, Fig. 2, and 4 4, Fig. 1, 55 respectively, showing the shell or containing-case. Fig. 5 shows another form of the apparatus, partly in longitudinal section and partly in diagram.

My invention is applicable to any usual or 60 preferred kind of jump-spark apparatus, the parts commonly composing such an apparatus including an induction-coil, a spark-plug, condenser, vibrator, battery or other source of current, and interrupter, the spark-plug 65 being mounted in the wall of an explosion-chamber or adjacent one end of the engine-cylinder and usually connected by suitable conductors in the circuit of the secondary of the induction-coil located at some remote 70 point wherever convenient the other parts also being located at various points to suit economy of space or other special requirements. My invention departs radically from this construction.

75

In the more elaborate form of my invention (shown in Figs. 1 to 4) it will be seen that I provide a shell A, preferably molded from hard rubber or otherwise formed of impermeable durable substance and comprising a 80 body portion a, containing a large chamber a', at one end of which is a smaller chamber a'', preferably separated from the induction-chamber by a wall a³, and at one side a medium-sized chamber a⁴ for the condenser and at the 85 opposite end a small chamber a⁵ for a vibrator. It will be understood that these chambers may be otherwise located and formed of different sizes and shapes, although for marine work the form and arrangement of case shown is 90 preferred. The case as thus formed and arranged is made as nearly of one piece as pos-

sible and the openings therein, which are necessary in order to get the contents assembled, are thereafter tightly closed, the result being that the entire apparatus is housed compactly 5 as a single article, as shown in the drawings.

Mounted in the end a^6 of the case A, containing the chamber a^2 , is a spark-plug a^7 , which may be of any kind suitable to the purpose. This spark-plug is herein shown as 10 movably mounted on a threaded boss a^8 , secured to an iron plate a^9 , permanently fastened to the head a^6 , the threaded external iron portion of the plug being also provided with threads a^{10} , by means of which it may be 15 mounted in usual position on the explosion-chamber b of the engine, as clearly shown in Fig. 5, and the internal core a^{12} , of insulating material, which carries at its outer end an electrode a^{13} to coöperate with the opposite electrode a^{14} of the plug, extends inwardly, as shown in Fig. 2, in constant contact with a spring contact-maker a^{15} , secured at a^{16} to the wall a^3 .

Within the chamber a^4 is mounted the induction-coil (shown in its simpler form in Fig. 5) 25 and having one end of its secondary s connected to the contact-maker a^{15} and the other end of said secondary being clamped beneath the plate a^9 . The primary p of the induction-coil 30 has one end also clamped beneath said iron plate a^9 and its other end soldered on the inner side or end of a binding-post. (Shown in Figs. 1 and 2 at a^{17} and in Fig. 5 at a^{18} .)

In the chamber a^4 is a condenser c , herein 35 shown as in shunt with the primary around the coil, the terminal a^{19} at one end thereof being soldered to the inner end of the binding-post a^{17} or a^{18} and the opposite terminal a^{20} thereof being secured to the under side of the 40 iron plate a^9 .

The chamber a^5 is provided for a vibrator d , which may be of any kind desired and is merely indicated herein without being shown in detail, being herein shown as operated by the coil 45 contained in the chamber a^4 , the latter being for this purpose wound in two parts on a U-shaped or horseshoe-shaped core a^{21} , the ends of which are offset at a^{22} to attract an armature a^{23} , coöperating with contact a^{26} on the 50 opposite side of the wall a^4 , this vibrator being interposed in the primary, which is connected therewith at a^{25} and a^{27} . If a vibrator is not used, the chamber a^5 is simply omitted, such a construction being shown in Fig. 5, 55 where instead of a double-coil case a single-coil case is shown.

From the foregoing description it will be seen that the secondary winding has no exposed connections, but is located directly in 60 connection with the plug, and also preferably all the parts are contained in the same case mounted directly on the plug, so that thereby no short-circuiting or deterioration can take place in the manner which has proved so dis-

astrous hitherto in connection with such trying situations as are met with in marine work, for example.

In use the plug is mounted in any convenient manner—as, for instance, directly on the chamber b , as shown in Fig. 5, at the end of 70 the engine-cylinder e —and the battery or other generator g is connected at one end to the binding-post a^{17} or a^{18} and at its other end is grounded, an interrupter h being interposed in usual manner.

My mechanism renders it exceedingly simple to repair or attend to the plug or any of the parts, the case being entirely self-contained, so that it can be screwed from the plug and the latter removed or any other part attended to. When the outer portion of the plug is unscrewed, the inner portion a^{12} may be withdrawn, and the separate chamber a^2 permits this to be done without any possibility of exposing the main parts of the apparatus 80 contained in the other chambers. Also when a vibrator is employed the end of the case containing the same is preferably removable, so that thereby the vibrator may be readily attended to. The other parts are sealed up 85 when originally made, and there is no likelihood that they will ever need attention. However, the construction is such that, if necessary, either chamber a^4 or a^5 (when the coil and condenser are kept in separate chambers) may 90 be opened without disturbing the other.

As already intimated, many changes in form, arrangement, and combination of parts may be resorted to without departing from the spirit and scope of my invention, and while I 100 prefer to employ all the parts together and to arrange them as herein shown it will be observed that certain of my claims are intended to be broad in scope and certain other claims are drawn to cover various subcombinations, 105 while a few of the claims are more specific.

Having described my invention, what I claim as new, and desire to secure by Letters Patent, is—

1. The herein-described means for adapting 110 sparking devices to marine work, consisting of an impervious case of heavy, durable, insulating material, provided with a coil-chamber, having an induction-coil sealed therein, a separate chamber containing a secondary 115 contact, and a spark-plug held in the wall of said case in engagement with said contact.

2. Ignition apparatus for marine work, comprising a moisture-proof case of heavy, durable material, having a plurality of tightly- 120 closed chambers, and containing induction apparatus, and a spark-plug removably mounted in said case to enter one of said chambers, the latter chamber being entirely sealed from the rest of the case and receiving therefrom 125 the terminals to coöperate with said plug.

3. Ignition apparatus for marine work, comprising induction apparatus sealed in a mois-

ture-proof case of heavy, durable material, a spark-plug removably mounted in the end of said case, and plug-retaining means coöperating with said plug to tightly close the case 5 thereat when the plug is in place.

4. Ignition apparatus for marine work, comprising induction apparatus sealed in a moisture-proof case, of heavy insulating material, having removably mounted in one end a spark- 10 plug, threaded at its outer end for supporting the ignition apparatus on the engine.

5. Ignition apparatus for marine work, comprising induction apparatus sealed in a durable impervious case, having an iron plate 15 tightly secured at one end and provided with plug-retaining means opening into the case, combined with a spark-plug adapted to be removably secured to said means, and, when so secured, having one of its electrodes extending 20 within the case in operative relation with said induction apparatus.

6. Ignition apparatus for marine work, comprising induction apparatus, sealed in a durable, impervious case, having an iron plate 25 tightly secured at one end and provided with plug-retaining means combined with a spark-plug held by said means, said plate constituting one conductor for said induction apparatus and the other being provided by the spark- 30 plug.

7. Ignition apparatus for marine work, comprising a strong and durable moisture-proof case having a plurality of chambers, including a coil-chamber, vibrator-chamber, and

contact-containing chamber, said coil-chamber being permanently and tightly partitioned from said other chambers and closed in operation but having means for access thereto, combined with a spark-plug, and induction apparatus, including a vibrator. 35

8. Ignition apparatus for marine work, comprising a strong and durable moisture-proof case provided at one end with a spark-plug and having a plurality of chambers, a two-part induction-coil wound on a U-shaped core 45 being permanently sealed in one chamber, and a vibrator contained in another chamber, the ends of said core being offset adjacent to the side of the case for economizing space in coöperation with the vibrator and for allowing 50 advantageous movement to the latter.

9. Ignition apparatus for marine work, comprising an impervious case of durable insulating material, containing an induction-coil, and having at one end a spark-plug mounted on a 55 conductor-plate, one end of the primary and also of the secondary being connected to said plate and the other end of the secondary being connected to the insulated electrode of the plug. 60

In testimony whereof I have signed my name to this specification in the presence of two subscribing witnesses.

HENRY C. FOLGER.
